(57) **CLAIM**

The ornamental design for a multimedia controller tray, as shown and described.

DESCRIPTION

FIG. 1 is a perspective view of a multimedia controller tray;

FIG. 2 is a top plan view thereof;

FIG. 3 is a front side view thereof;

FIG. 4 is a right side view thereof;

FIG. 5 is a left side view thereof; and,

FIG. 6 is a rear side view thereof.

The dashed lines in the drawings are shown for environmental purposes and form no part of the claimed design.
